UNITED STATES PATENT OFFICE

2,294,454

ENGINE-DRIVEN PUMP

Lawrence Hathaway and John Thomas Wood disse, Coventry, England, assignors to Coventry Climax Engines Limited, Coventry, England

Application June 9, 1941, Serial No. 397,336
In Great Britain November 8, 1940

6 Claims. (Cl. 103—113)

This invention relates to an engine-driven pump, particularly for fire-fighting purposes, of the kind having a cooling system, for the engine, which involves sending some of the water being pumped by the pump through a heat-exchanger associated with the engine, or directly through the engine jacket. The supply of such cooling water from the pump is under the control of a valve, and this must be closed when the pump is being started up, in order to allow of the priming of the latter. In addition, a priming means is provided having a valve by means of which it can be connected with the pump for priming purposes.

(It may here be mentioned that it has already been proposed that a valve for connecting a priming means, of the exhaust-gas-ejector type, with the pump and a valve for controlling the action of the ejector should be interconnected for operation by a common control.)

It is found that in some cases users of the unit have forgotten to open the valve, controlling the supply of cooling water from the pump, when priming has been effected, in consequence of which the engine becomes over-heated, with disadvantageous results. In other cases the valve has not been closed when the pump was to be primed, with the result that priming could not be effected.

It is our main object to provide a simple remedy which will obviate these defects.

It is a further object to arrange for the valve controlling the supply of cooling water from the pump, and the valve controlling the connection of the pump to the priming means, to be interconnected such that a single control will close one of the valves and open the other, and vice versa.

In applying the invention to a unit of the kind in which the engine is cooled on the "inter-cooler" system, we may mechanically connect the movable element of the valve, controlling the supply of cooling water from the pump to the coiled pipe of the "inter-cooler" tank, with the movable element of the valve controlling the connection of the priming means to the pump, the arrangement preferably being such that in moving the common control the first of these valves will be entirely closed before the second of the valves starts to open.

In a preferred arrangement, however, we group the valves together and use a common rotary valve element having appropriate transverse bores which co-operate, respectively, with the two passages in a combined valve body in the manner specified. Thus, we may make use of a casting with the necessary passages therein communicating with a common bore in which the rotary valve element is disposed to be worked by a control lever.

For a better understanding of the objects and advantages of the invention attention should be directed to the following description in which reference is made to the accompanying sheets of drawings, wherein:

Figure 1 is a part-sectional diagrammatic view of an engine-driven pump, the engine of which is cooled by the "inter-cooler" system, adapted according to the invention, though, in point of fact, the pump is in the main omitted, only the bulkhead or panel between it and the engine being shown;

Figures 2 and 3 are elevations at right angles to one another mainly of the upper half of the pump and the control valve of the invention; and

Figure 4 is a sectional plan of the control valve.

The drawings show at 10 an internal-combustion engine of any appropriate form adapted to 20 drive a coaxially-disposed pump 12 of the centrifugal type having a volute chamber part of which is indicated at 13. The engine is cooled by water being circulated through its jacket and through an "inter-cooler" tank 14, 15 indicating the outlet pipe from the engine jacket to the "inter-cooler" tank and 16 the return pipe from the latter to the engine jacket. The "inter-cooler" coil 17 is supplied by the pipeline 18 and exhausts along the pipeline 19, the pipe 18 receiving water at 20 from the pump outlet.

The priming of the pump is effected by an exhaust-gas-ejector, indicated at 21, which is of known form. The exhaust manifold 22 of the engine can connect with a Venturi tube 23 to the annular space around which, at 24, is connected a suction pipe 25 leading to the inlet or suction side 26 of the pump.

The normal exhaust from the engine takes place along the exhaust pipe 27. When priming is to be effected the clapper valve 28 is moved to the position indicated by the chain line 28a to close the exhaust pipe 27 and the exhaust gases then pass through the Venturi tube 28, serving for evacuating air from the pipe 25.

The clapper valve 28 is operable by a hand lever 31 which is connected with the valve by an arm 32 and link 33 and is biased to the position shown by means of a spring 35. 37, 38 represent flanges to which the pump delivery valves (a pair in this instance) are connected.

In the present arrangement the pipeline 18 and the pipeline 25 are brought beside one another in the vicinity of the bulkhead or panel 39 between the engine and the pump, and the flow in these pipes is controlled by a common rotary valve element 41 on which the hand lever 31 is fast. In Figure 1 the valve casing 42 is shown as having a pair of straight-through passages leading to the tapered bore in which the tapered rotary element 41 is disposed, but in practice it

is more convenient for the passages in the valve casing to be right angled, as indicated by Figures 2 to 4. The rotary element has two through bores 43 which are, as shown most clearly in Figure 4, at right angles to one another and are positioned along the element to connect, respectively, with the two passages for the pipes 18 and 25 in the valve casing 42. Pins 45 (Figure 4) carried by the valve casing coat with an appropriate abutment (indicated at 46) on the rotary element to limit the movement of this to 90 degrees to bring one or other of the bores 43 into operative relation with its associated passage.

With the hand lever 31 in the position shown the priming passage 25 is closed, the main exhaust pipe 27 is open, and cooling water is being supplied by the pump along the pipeline 18 to the coil 17 of the "inter-cooler" tank, thus preventing the engine from over-heating, this being the normal position of the lever 31 when the engine is working. When starting up, however, no cooling water is supplied to the "inter-cooler" coil, as this is not necessary when starting up, or can be omitted for the short period while priming is being effected; but the hand lever 31, being turned through 90 degrees, the pipeline 18 is closed and the priming pipe 25 is open, whilst, in addition, the main exhaust pipe 27 is closed so that the exhaust gases pass through the Venturi tube 23 and by ejector action introduce a flow of air along the pipe 25, thus priming the pump. Once priming has been completed the hand lever 31 can be returned to its normal position, as shown in the drawings. As previously mentioned, it is biased in this position and should therefore be held in the priming position for the short period during which priming takes place, when the engine will not be positively cooled.

Thus, by means of the invention it is impossible for the water cooling valve (pipe 18) to be inadvertently left closed after the pump has been primed, or for anyone to attempt the priming of the pump without first closing the pipe 18 and then opening the priming pipe 25.

Whilst for the sake of simplicity we have shown the combined valve unit mounted on the panel 39, it will be obvious that it could be mounted wherever convenient. For example, if mounted directly on the volute body 13 of the pump some of the passages could be cored in the pump body, thus eliminating some of the copper pipes and joints between the pump and valve unit.

What we claim as our invention and desire to secure by Letters Patent of the United States is:

1. In combination, a motor, a cooling means for the motor, a pump driven by the motor, a normal exhaust for the motor, a secondary exhaust for the motor, exhaust valve means to open and close the normal exhaust, a suction device in the secondary exhaust, a priming conduit connecting the suction device and pump, a liquid conduit connecting the cooling means and the exhaust of the pump, coordinate valve means in the conduits to open and close same only alternately, and operating means both for the exhaust valve means and coordinate valve means adapted to cause the exhaust valve means to close and open the normal exhaust simultaneously with the opening and closing of the priming conduit.

2. The combination of claim 1 characterized by biasing means coupled to the operating means to bias the parts to non-priming position.

3. The combination of claim 1 characterized by biasing means coupled to the operating means to bias the parts to non-priming position, said operating means having a part for manually shifting the same to priming position.

4. The combination of claim 1 in which the coordinate valve means are rigidly connected to the operating means and both are remote from the exhaust valve means, with linkage connection between the operating and exhaust valve means, the operating means having a manual part for engagement to move the operating means to a priming position, and biasing means acting reversely on the operating means to bias the parts to a non-priming position.

5. In an engine driven pump, an engine having an exhaust pipe, an intercooler for the engine and pump, an exhaust gas ejector pump priming mechanism operatively connected to the engine exhaust pipe, a conduit connecting the priming mechanism to the pump, a two position valve disposed in the operative connection between the priming mechanism and engine exhaust pipe to open and close communication between the priming mechanism and engine exhaust pipe, a two way, two position valve mechanism controlling the conduit between the pump and intercooler and the conduit between the priming mechanism and pump, said valve mechanism in one position opening the intercooler conduit and closing the priming conduit and in its other position closing the intercooler conduit and opening the conduit to the priming mechanism, a control lever to move the valve mechanism to one or the other of its positions, and means operatively interconnecting the two position valve and the control lever to close the two position valve when the valve mechanism control lever is in its first named position and to open the two position valve when the valve mechanism control lever is in its second named position.

6. In an engine driven pump, an engine having an exhaust pipe, an intercooler for the engine and pump, an exhaust gas ejector pump priming mechanism operatively connected to the engine exhaust pipe, a conduit connecting the priming mechanism to the pump, a two position valve disposed in the operative connection between the priming mechanism and engine exhaust pipe to open and close communication between the priming mechanism and engine exhaust pipe, a two way, two position valve mechanism controlling the conduit between the pump and intercooler and the conduit between the priming mechanism and pump, said valve mechanism in one position opening the intercooler conduit and closing the priming conduit and in its other position closing the intercooler conduit and opening the conduit to the priming mechanism, a control lever to move the valve mechanism to one or the other of its positions, and means operatively interconnecting the two position valve and the control lever to close the two position valve when the valve mechanism control lever is in its first named position and to open the two position valve when the valve mechanism control lever is in its second named position, and means biasing the control lever and valve mechanism to its first named position.
